UNITED STATES PATENT OFFICE

1,952,910

POLISHER WITH RESERVOIR

Alonzo G. Decker, Baltimore, Md., assignor to
 The Black & Decker Manufacturing Company,
 Towson, Md., a corporation of Maryland

Application November 14, 1930, Serial No. 495,637

5 Claims. (Cl. 91—39)

The art of cleaning lacquered and similar surfaces particularly the surfaces of motor vehicle bodies, and applying a thin film of wax which is thus brought to a high polish, has been performed by hand with a reasonable degree of success. In accordance with the practice as thus developed, the process consists in first cleaning the car by washing it with water with or without a chemical solvent. When it has been satisfactorily cleaned, wax is spread on the surface and rubbed in by hand until the work attains a sufficient gloss. To perform this operation in a satisfactory manner requires a great deal of care and consumes so much time that cleaning and waxing in this way is quite expensive.

As a substitute for the hand method, the assignee of the present application has developed a method of polishing by the use of a portable power driven rotary tool which has proved highly successful. This consists in rotating a wool or similar pad in close contact with the work, the pad being moved at a peripheral speed of from 1600 to 4000 feet per minute. In connection with this operation, a cleaning and polishing compound in liquid form is used, the liquid ingredients being preferably such as to evaporate quickly under the action of the polishing pad and the draft or windage created by it so that the cleaning elements of the dirt coating dissolved by the liquid are thrown off in the form of powder leaving an oily waxy residue which is immediately attached or caused to adhere to the surface and brought to the proper lustre.

In the practice of the applicant's method referred to, a cleaning and polishing liquid which in the preferred form consists of a fine abrasive, water, a hydrocarbon solvent for grease and a small amount of wax in suspension is spread thinly upon the surface to be cleaned, the pad rotating at the speeds specified is then held in contact with the surface and passed over the surface to be treated.

To spread the cleaning and polishing material over the surface in this way preliminary to polishing, involves something in the nature of a hand operation prior to the effective use of the portable power operating means by which the pad is rotated.

The object of the present invention is to avoid the necessity for the preliminary hand operation by feeding the cleaning and polishing compound automatically to the operative surface of the pad while the pad is either stationary or rotating and prior to the final polishing operation.

In accordance with the preferred operation of

the tool the polishing compound which is a fine liquid, is fed through the pad when the latter is not rotating, the pad being held against the surface to be polished so that the liquid runs on to the surface and is spread around by moving the pad over the desired area. The feed being then shut off, the motor is started and the polishing operation proceeded with as previously outlined. The apparatus comprises a portable electric polisher equipped with a disklike polishing pad mounted on the tool and provided with an outlet leading from the reservoir through the spindle of the tool and into the central portion of the pad. The equipment also includes a valve arrangement on the reservoir and a spring feeding device so that the liquid can be fed as required though the spring feed is not always essential.

In the accompanying drawings I have illustrated a portable power driven rotary polisher embodying the features of my invention in the preferred form.

In the drawings:

Figure 1 is a side elevation of a polishing tool equipped in accordance with one form of the invention.

Figure 2 is a fragmentary elevation on a somewhat larger scale and from the same point of observation, the polishing reservoir and a portion of the spindle and connecting parts being shown in vertical central section.

Figure 3 is a top plan view of the reservoir and a fragment of the controlling lever.

Figure 4 is a vertical central section of the tool taken through the axis of the spindle, the motor casing being shown fragmentarily in elevation. In this view another type of valve control is shown.

Figure 5 is a top elevation of the construction shown in Figure 4 on a smaller scale.

Referring to the drawings by numerals, each of which is used to indicate the same or similar parts in the different figures, the construction shown in Figure 1 comprises a motor housing 1, having a gear casing 2 secured to one end of the housing and a hand grip 3 secured to the other end. The grip or grip casing 3 preferably encloses a suitable switch mechanism and is provided with a projecting switch lever 4, which may be in the form of a trigger or similar device. The motor shaft 5, Figure 4, is shown as provided with a pinion 6, which meshes with a gear 7 connected to the spindle 8 to rotate therewith in any convenient way as by means of key 9. The spindle 8 is mounted in bearings 10, 11 in the gear cas-

ing in which it is located at right angles to the motor shaft 5, projecting downwardly from gear casing 2.

- The spindle 8 is provided on its projecting end 5 with a polishing disk 12 of any suitable type, the preferred type being shown. This disk 2 is held on the spindle by means of interengaging threads 14 and 15, formed on the reduced end 16 of the spindle and a corresponding opening in the disk 17 or disk support 17. The spindle is also shoudered at 18 to position the disk and the latter is further secured by a nut 19 on the lower end of the shaft which nut enters a depression in the disk not fully illustrated.
15. The construction further includes in the preferred form a longitudinal duct 20 extending from one end to the other of the spindle and terminating at its lower end in a downwardly disposed opening 21 at the lower end of the spindle 20 adjacent the operative surface 22 of the pad 24.

The invention also relates to the provision at the other end of the spindle of a reservoir 25 which in the form of the invention shown has a central shank 26 extending downwardly from its bottom wall. This is threaded into the gear casing and its reduced lower end 27 enters a corresponding socket 28 in the upper end of the spindle, having a clearance so slight as to prevent the escape of the polishing material. The shank 26 is provided with a central duct 29 extending downwardly from a valve seat 30 in the bottom of the reservoir and connecting at its lower end with the duct 20 in the spindle. The reservoir 25 is shown as in the form of a cylinder 35 or equivalent construction containing a piston 31 mounted to slide freely therein, but having a fluid tight engagement with the cylinder walls.

While the piston may be of any suitable construction, in the form shown, it is very much like the ordinary tire pump pistons including the usual cup shaped washer 32. The opening in the cup being disposed downwardly toward the liquid being fed tends to inflate it against the walls and prevent leakage of this liquid past the piston. 45. This piston as shown is provided with a bushing 33 which operates as a slide bearing for the valve stem 34. This member 33 is shown as provided at its upper end with an angular nut or head 35 which bears against an upper metal disk 35, and 50 has a downwardly projecting threaded member 36 which may engage corresponding threads in the aperture 37 in a metal disk or plate 38 inside the cup washer 32 holding the latter in position and holding the piston parts in their assembled 55 relation.

The polishing compound is retained at 39 in the lower end of the cylinder and the piston 31 is pressed down against the polishing compound 60 which is preferably liquid by means of a helical compression spring 40 located in the upper end against the cylinder head or cover 41 and at its lower end against the piston 31.

The cap or head 41, Figure 4, is shown as taking over the top of the cylinder having a threaded engagement therewith at 42 and is provided preferably in a central location with a threaded opening 43. This threaded opening contains a screw plug 44 engaging the thread in the opening and 70 having at its upper end a knurled head 45, the plug and head being secured to the upper end of the valve stem 34, the lower end of which is provided with a valve member 46 which engages and cooperates with the valve seat 30 at the bottom of the reservoir and at the upper end of the duct 75

29, 20, where it leaves the bottom of the reservoir 25.

In the operation of the apparatus of this type, the pad 24 being placed on the surface to be cleaned, the valve 46 is opened by unscrewing the plug 44, engaging the same by the knurled head 45 which may be connected to the spindle 34 either positively so as to rotate the valve, or otherwise so as to merely raise it as preferred. A very slight opening such as can conveniently be obtained in this way, is sufficient to permit just the right amount of liquid to flow downward on to the surface to be treated, indicated at 46, and the pad and tool being moved by hand, the pad being preferably not rotated at the time though it may be rotated if desired, the compound is spread over the desired area of surface following which the valve is closed and the pad operated by means of the motor to give the desired effect of cleaning and polishing as already outlined.

90 Referring now to the type of machine illustrated in Figures 1, 2 and 3, the arrangement of the motor housing 1, gear casing 2, spindle 8 and reservoir or cylinder 25 is the same in both constructions as is also the piston 31 and valve stem 100 slide bearing 33 therein.

The valve stem 50 and the cylinder head 51 are, however, differently arranged. The cylinder head or cover 51 is provided with a central slide bearing 52 extending in the direction of the axis 105 and the valve stem 50 is mounted to slide therein as well as in the bearing 35 which latter is sufficiently tight to prevent the escape of the liquid. In the construction shown the spindle 50 carrying the valve 56, instead of being operated by a screw thread, slides through the head 51 in the direction of its length, the valve being normally closed by means of a coil or helical spring 57 which engages at one end a suitable collar 58 secured to the valve stem and at the other end 115 bears against the bottom surface 59 of the cylinder cover or head 51. The valve stem 50 extends well above the cylinder head 51 in the closed position of the valve and is provided at its upper end with a shoulder or head 60 which is engaged from beneath by the forked or other suitable apertured end 61 of a hand lever 62 which extends longitudinally of the motor housing 1 and gear casing 2 along the top of the same, being pivotally mounted at 63 on the motor housing just forwardly of the center of the lever which is shaped to conform to the general contour of the top side of the apparatus. The rear end of lever 62 has a thumb rest or presser end at 64 in convenient relation to the grip 3. The rear or manually engaged end of the lever 62 is supported in any suitable manner as by means of a spring stud or button 65 located on the motor housing so that it is held normally out of engagement with the head 60 of the valve stem, permitting the valve to remain normally closed.

125 When in the operation of the tool it is desired to spread the liquid over the surface to be treated, the motor being preferably stopped, the rear end or operable end 64 of the hand lever 62 is pressed downwardly by the thumb of the operator, swinging the forward end of the same, i. e., the apertured end 61, upwardly against the head 60 of the valve stem which stem is thereby raised, raising the valve 56 from its seat and permitting any 145 desired amount of the liquid to escape. The valve 56 is thus so conveniently and quickly opened and closed that the liquid may be most uniformly and economically distributed over the surface to be treated. When the polishing com- 150

- 5 pound has been thus spread on the surface, the hand lever is released and the valve permitted to close by the operation of the spring 57, and the switch lever 4 being pressed, the pad is placed in 5 rotation and the cleaning and polishing operation completed.
- 10 I have thus described specifically and in detail a polishing tool having a reservoir for the polishing compound and a valve means therein embodying the features of my invention in different alternative forms, however, the specific terms herein are used descriptively rather than in a limiting sense, the scope of the invention being defined in the claims.
- 15 5. What I claim as new and desire to secure by Letters Patent is:
1. In a hand controlled manually portable power driven rotary cleaning and polishing tool having a hand grip a hollow spindle, means supporting a polishing pad thereon, a reservoir for cleaning and polishing liquid connected to the upper end of said spindle passage, said hollow forming a passage for liquid from said reservoir to said pad, a piston in said reservoir operating 25 to force the liquid through said passage, a valve controlling said passage and means extending upwardly through said piston for operating said valve to deliver a supply of liquid to the pad at the will of the operator and to discontinue the 30 same, said valve operating means sliding freely through said piston, and including manually engaged means immediately adjacent said grip so that the valve can be operated by the gripping hand without releasing the grip.
  - 35 2. In a hand controlled manually portable power driven rotary cleaning and polishing tool a hollow spindle, means supporting a polishing pad thereon, a reservoir for cleaning and polishing liquid connected to the upper end of said passage, 40 said hollow forming a passage for liquid from said reservoir leading to the pad, a spring pressed piston in said reservoir operating to force the liquid through said passage, a valve controlling said passage and manually engaged means extending 45 upwardly through said piston into convenient reach of the operator, said manually engaging means sliding freely through the piston in operating said valve to control the supply of liquid to the pad.
  - 50 3. In a hand controlled manually portable power operated cleaning and polishing tool, said tool
- having a hand grip and being of the rotary type of tool having a rotary hollow spindle, means for operating the same and means for securing a polishing pad to the lower end of the spindle and said tool, a reservoir for cleaning and polishing liquid mounted on the said tool, said hollow providing a passage for liquid from the reservoir to the pad, a spring operated piston in the reservoir to apply pressure to the liquid and force the liquid through said passage, a valve controlling said passage, a spring tending to close the valve and a lever immediately adjacent the hand grip and adapted to be enclosed within and operated by the operator's hands in holding the tool for controlling the valve.
4. In a manually controlled and supported power operated portable cleaning and polishing tool of the rotary type having a hollow spindle, means for operating the same and means for securing a polishing pad to the lower end of the spindle, a reservoir for polishing compound mounted on said tool, said hollow providing a passage for liquid in passing from the reservoir to the pad, a spring operated piston in the reservoir operating to force the liquid through said passage, a valve controlling said passage, a spring tending to close the valve, the tool having a hand grip, a switch immediately adjacent said grip, and a lever for operating said valve against the spring having an engaging portion immediately adjacent the grip.
5. In a manually controlled and portable power driven polishing tool of the rotary type having a hand grip and hollow spindle, means for securing a polishing pad to the lower end of the latter, a reservoir, a hollow in the spindle serving as a passage for polishing liquid from the reservoir to the pad, a valve controlling said passage, a piston in the reservoir for applying pressure to the liquid tending to force it through said passage, a spring tending to advance the piston and expel the liquid through the passage to the pad, said piston having an opening, and the valve having a stem sliding freely through and fitting in said opening and means in the form of a lever having a manually engaged portion in close relation to said hand grip for operating the valve, at the will of the operator and by means of the gripping hand.
